UNITED STATES PATENT OFFICE.

WAINWRIGHT B. GERVAIS, OF CHICAGO, ILLINOIS, ASSIGNOR TO VARIETY MANUFACTURING COMPANY, OF CHICAGO, ILLINOIS, A CORPORATION OF ILLINOIS.

DOOR.

1,171,424.

Specification of Letters Patent. Patented Feb. 15, 1916.

Application filed March 30, 1914. Serial No. 828,156.

To all whom it may concern:

Be it known that I, WAINWRIGHT B. GERVAIS, a citizen of the United States, and a resident of Chicago, in the county of Cook and State of Illinois, have invented a certain new and useful Improvement in Doors, of which the following is a full, clear, concise, and exact description, reference being had to the accompanying drawings, forming 10 a part of this specification.

My invention relates to doors and more particularly to metallic doors employed for store-rooms.

My invention contemplates a door constructed in such a way as to permit expansion of the door frame and the plate mounted thereon, and in addition, the door is built up in such a way as to minimize the number of operations necessary to make a 20 complete door.

My invention consists of a frame of suitable structural shapes, and a plate, the tops and side edges of which are pressed into firm engagement with the edges of the 25 frame. In mounting the plate upon the frame, there is no riveting done whatsoever. The edges of the plate are crimped and then the plate is slipped over the frame and subsequently the crimped edges of the plate are 30 pressed into engagement with the frame. This arrangement provides a structure whereby the edges of the door are greatly improved in appearance. The mounting of the plate upon the frame without the use of 35 rivets prevents the buckling of the parts in case of fire.

My invention will be better understood by referring to the accompanying drawings in which—

40 Figure 1 is an elevational view of a door embodying the features of my invention. Fig. 2 is a cross-sectional view taken on line 2—2 of Fig. 1. Fig. 3 is an enlarged sectional view taken on line 3—3 of Fig. 1. 45 Fig. 4 is a rear view of the door showing the frame and the plate mounted thereon. Fig. 5 illustrates the plate before the top and sides have been crimped. Fig. 6 illustrates a top view of the plate after the edges 50 have been crimped.

Referring first to Figs. 4, 5 and 6, I have illustrated a rectangular frame comprising the side members 7 and 8, and the top and bottom members 9 and 10, respectively, and 55 intermediate members 11. All these mem-

bers are bars of angle iron, and are connected by means of angular pieces 12—12. It will be noted that the top and side members present a surface lying in one plane and the bottom member 10 presents a wide surface of the side of the angle bar to the floor. After the frame has been constructed it is ready to receive the plate 13 and in order to prepare this plate to be slipped over the sides and top of the frame, the top and side 30 edges 14 and 15 respectively are crimped along the dotted lines as shown in Fig. 5, and are forced into the positions as shown in Fig. 6. After this crimping action has been completed, the plate 13 is slipped over 35 the frame, after which the top and side edges 14 and 15 respectively are pressed or stamped into firm engagement with the edges of the rectangular frame. It will thus be noted that very few operations are required 40 in order to construct a door of the class described, the riveting being employed only to connect the different members of the rectangular frame. After the plate 13 has been put in place upon the framework the hinges 45 16—16 are mounted upon the completed door and the latching members 18—18 are also put in place connected by means of the rod 50 19.

As shown particularly in Figs. 2 and 3, 55 the edges of the completed door present a rounded appearance and thus improve the door to a great extent, in addition to having a solid bearing surface against the metallic parts of the opening in the wall. The bottom of the door presents a wide surface to 60 the floor and thereby strengthens the lower portion of the door, in addition to preventing the flames, in the case of fire, from passing underneath said door.

It will be obvious that my invention provides a door which is constructed in a manner radically different from anything in the prior art, and has advantages which the structures of the prior art do not possess. 65 The mounting of the plate 13 upon the rectangular frame without employing rivets provides for relative movement of these parts when heated in case of unequal expansion. The folding of the edges of the door plate on the frame has another advantage in that it stiffens the edges of the door and thus provides a very close fit between the door and the frame mounted on the building. The door, as constructed in ac- 70 75 80 85 90 95 100 105 110

cordance with my invention, has a wide engagement with the frame disposed around the opening of the building and thus prevents the passage of the flame in case of fire.

5 While I have herein shown and described one form of my invention, I do not wish to be limited to the precise arrangement shown, inasmuch as it will be apparent that modifications may be made without departing 10 from the spirit and scope of my invention.

I claim as new and desire to secure by Letters Patent:

15 In a door frame of L shaped angle bars, the bars on the top and both sides having one flange of each forming an open frame,

the other flange extending out to form a peripheral flange about said frame, a bar joining the bottom of said side bars and a sheet of sheet metal lying loosely on and closing said open frame and being bent over the 20 latter flanges of said angle bars, said latter flanges being adapted to be outside of the door casing.

In witness whereof, I hereunto subscribe my name this 16th day of March, A. D. 25 1914.

WAINWRIGHT B. GERVAIS.
